SIGNAL-INDICATOR DEVICE
Charles T. Mulligan, 3504 Everton St., Wheaton, Md.
Filed Jan. 2, 1962, Ser. No. 163,503
5 Claims. (Cl. 116—133)

This invention relates to signal-indicator devices and, more particularly, to a signal-indicator device for use by an individual while officiating a football game.

In most instances, individuals while officiating a football game must carry, employ and operate at least two separate and independent devices, which are usually in the form of an audible signal, like a whistle, for signaling the end of a down, time out, time in, end of play period, etc.; a visual indicator for indicating the downs of play, such as first, second, third and fourth as well as no down plays, such as kickoffs, extra points, etc.; time indicators, such as stop watches for indicating time intervals for the play periods, time outs, etc.; various types of flags for indicating infractions of the rules, and other devices, such as pistols which may be employed to signal the end of a play period.

The audible signal used by individuals while officiating a football game is usually a whistle which may be carried about the neck of the official, by suitable lanyards, or the like, or carried by the hand of the official during the game. Whether the whistle is carried about the official's neck or in the hand of the official usually depends upon the particular personal preferences of the individual.

However, in using the hand-carried type of whistle, an official is usually protected against being guilty of a "quick whistle" since the hand whistle must first be brought to the official's mouth before the signal may be given while a whistle which is supported by a lanyard about the official's neck is usually carried in the official's mouth during the play period which enables the official to give the signal which, in many instances, might cause the official to be guilty of giving a "quick whistle" before the ball should have been signaled or declared dead.

The usual visual indicator for indicating the down of a series of plays normally takes the form of a hand-carried indicator device wherein there is employed indicia which is selectable on option of the official to indicate the down number of the upcoming play with the indicia being selectable, as desired, by manual operation of the fingers or thumb of the official's hand.

Hence, officials of football games who prefer to use a hand-carried whistle are somewhat handicapped by reason of the fact that the other implements employed, such as the watches, flags, pistols, and particularly the indicator device for indicating the down of the upcoming play are also generally hand operated by the fingers or thumb of the individual's hand.

Further, it has been found that since officials while in the process of officiating a football game must be active in other aspects than merely watching the play; for instance, between the downs of play the ball must be retrieved and properly positioned for the next play which may require that the ball be passed from one official to another official; that in this type of activity, it is highly desirable that the official have the fingers and thumbs of his hand free to handle the ball.

Accordingly, it is an object of this invention to provide a signal-indicator device for producing an audible signal and for indicating a visual indicia for use by an individual while officiating a football game with structure for enabling the signal-indicator device to be carried conveniently by and secured to the fingers of the hand of the official.

It is also an object of this invention to provide a signal whistle and a down indicator with structure for enabling the signal whistle and down indicator to be conveniently hand carried by the fingers of an individual while officiating a football game.

2

Another object of this invention is to provide a unitary signal-indicator device which includes a signal whistle and a down indicator which are connected together by structure in a manner which enables an individual to conveniently hand carry the signal-indicator device while officiating a football game.

An additional object of this invention is to provide structure which connects and secures a signal whistle to a down indicator to define a signal-indicator device which may be conveniently hand carried by an individual while officiating a football game.

Other objects, advantages and important features of the invention will be apparent from a study of the specification following, taken with the drawing, which together describe, disclose and illustrate certain embodiments or modifications of the invention and what is now considered to be the best mode of practicing the principles thereof. Still other embodiments or modifications may be suggested to those having the benefit of the teachings therein and such other embodiments or modifications are intended to be reserved especially as they fall within the scope and breadth of the subjoined claims.

In the drawing:

FIGURE 1 is a side elevational view of a signal-indicator device having hand-hold structure incorporated therewith according to the concept of this invention;

FIGURE 2 is a front elevational view of the signal-indicator device of FIGURE 1 as viewed from the left thereof;

FIGURE 3 is a bottom view of the signal-indicator device illustrated in FIGURE 1;

FIGURE 4 is a longitudinal sectional view taken along the line 4—4 of FIGURE 1, looking in the direction of the arrows;

FIGURE 5 is a side elevational view similar to FIGURE 1 but illustrating a modification of the signal-indicator device, and

FIGURE 6 is a side elevational view similar to FIGURES 1 and 5 but illustrating still another modification of the signal-indicator device.

Attention is now directed to FIGURE 1 of the drawing wherein there is illustrated a signal-indicator device 10 having an audible signal 12 in the form of a whistle, a visual indicator 14 in the form of selectable indicia, and structure 16 having an arrangement 18—20 in the form of at least one element or member for securing the signal-indicator device 10 to the index and middle fingers, not illustrated, of an individual's hand to enable the signal-indicator device 10 to be conveniently secured thereto and carried thereby in a manner which will enable the individual to have use of the fingers or thumb of the hand which is carrying the signal-indicator device 10 while officiating a football game and enable the individual to perform the many tasks required by an official while officiating a football game as well as providing easy access to and use of the signal-indicator device 10, when required.

The signal-indicator device 10 may be formed of any suitable metallic material or plastic substance, such as nylon or the like, and it is to be noted that the structure 16 is joined or otherwise secured directly to, or may be formed integral with, both the audible signal 12 and the visual indicator 14, to define a unitary device with the structure 16 being disposed intermediate of and extending between the audible signal 12 and the visual indicator 14 so that the visual indicator 14 may be positioned adjacent to the palm of the individual's hand, not illustrated, and the audible signal 12 may be adjacent to the back of the individual's hand, also not illustrated, when the signal-indicator device 10 is in use by the individual in the process of officiating a football game.

The signal-indicator device 10 is intended to be used by an individual for officiating a football game with the audible signal 12 being employed to signal certain game conditions, such as the end of a down, time out, time in, end of a play period, etc., and the visual indicator 14 being employed to indicate the down number of a play, i.e., first, second, third or fourth, as well as no down plays, such as kickoffs, extra points, etc.

As is customary as mentioned above and as illustrated in the figures of the drawing, the audible signal 12 is preferably in the form of a whistle.

Also, as illustrated in the drawing, the visual indicator 14 may take the form of a housing 22 formed of substantially like top 24 and bottom 26 half portions which may be secured together by a press fit or some other suitable securing means to define a chamber 28 wherein there is rotatably mounted, by means of a shaft 30, fixed between the top 24 and the bottom 26 portions of the housing 22, a disc 32 having indicia 34 thereon with the indicia 34 being preferably numerals in character, such as 0, 1, 2, 3, and 4, or the like, with the indicia 0 being used for indicating a no down play; the indicia 1, 2, 3, and 4 being used, respectively, to indicate the sequence of downs in a given series of plays of a football game.

The outer peripheral edge portion 36 of the disc 32 is preferably knurled or otherwise roughened to facilitate in the positioning of the disc 32 in a manner so that the selected one of the indicia 34 may be viewed through an aperture 38 formed in the bottom portion 26 of the housing 22 with the aperture 38 being formed therein at a location which may be in registry with selected locations of the indicia 34 on the disc 32.

Suitable bias 40 in the form of a resilient spring-like member may be interposed between the bottom portion 26 of the housing 22 and the disc 32 to restrain the disc 32 against inadvertent, accidental rotation so that the selected indicia 34 may be maintained in the desired position for viewing through the aperture 38 in the bottom portion 26 of the housing 22.

It is also to be noted that a part 42 of the disc 32 projects beyond the confines of the housing 22 and is positioned during use of the signal-indicator device 10 in close proximity to the thumb, not illustrated, of the individual to enable the thumb to act on the knurled outer peripheral edge portion 36 of the disc 32 and exert a force thereon to overcome the bias 40 and reposition the disc 32 as desired to select a given one of the indicia 34 for viewing through the aperture 38 in the bottom portion 26 of the housing 22 and so indicate to the official the selected down of a given series of plays in a football game.

The housing 22 of the visual indicator 14 may be shaped, if desired or requested, to conform to the configuration of an individual's palm, fingers, thumb, etc., when the hand of the individual is clenched.

The structure 16 may take any suitable form and be bodily flexible or bodily rigid, as desired, provided that the arrangement 18-20 of the structure 16 is capable of securing the signal-indicator device 10 to the hand of the individual so that the audible signal 12 may be disposed to the back and the visual indicator may be disposed adjacent to the palm, as described and disclosed above.

The arrangement 18-20 of the structure 16, as illustrated in FIGURES 1 and 2 of the drawing, is shown in the form of a pair of annular endless ring-like elements or members having the peripheral edge portions thereof joined or otherwise secured together at a location 44 by suitable means or formed integral with each other in a manner which enables the individual's index finger, not illustrated, to pass through the element or member 18 and the individual's middle finger, not illustrated, to pass through the element or member 20. The ring-like elements or members 18 and 20 are also each respec-

tively joined, secured or formed integral with the top portion 24 of the housing 22 along the peripheral outer edge portions thereof at locations 46-48 thereon which are each circumferentially spaced from the location 44 so that the housing 22 will be disposed within the confines of the palm, not illustrated, of the individual's hand with the aperture 38 in the bottom portion 26 of the housing 22 facing generally outwardly therefrom and the part 42 of the disc 32 being in close proximity to the thumb, not illustrated, of the individual.

On the peripheral outer edge portion of the ring-like element or member 18 at still another location 50 thereon, which is substantially diametrically opposed to the location 46 whereat the visual indicator 14 is secured thereto, the ring-like element 18 is secured, joined or formed integral with the audible signal 12 so that the audible signal 12 will be disposed to the back, not illustrated, of the individual's hand for easy access thereto by the individual's mouth during the use of the signal-indicator device 10, as may be required.

In passing, it is to be understood that while the modification of the signal-indicator device 10, as illustrated in FIGURES 1 and 2 of the drawing, show the top portion 24 of the housing 22 being secured, joined or otherwise integrally formed at the locations 46 and 48 to the ring-like elements 18 and 20 respectively, that the top portion 24 of the housing 22 may, if desired, be formed integral with, joined or otherwise secured to only one of the ring-like elements or members 18 or 20. Also, in the same manner, the audible signal 12, while illustrated in FIGURES 1 and 2 of the drawing as being secured, joined or formed integral with only the ring-like element or member 18 at the location 50, that, if desired, the audible signal 12 may be joined, secured or formed integral with both of the ring-like elements or members 18-20 or only the ring-like element 20.

In this way, the structure 16 is interposed between the audible signal 12 and the visual indicator 14 in a suitable manner, such as being secured, joined or formed integral therewith, which enables both the audible signal 12 and the visual indicator 14 to be easily accessible to the individual's mouth and thumb, respectively, as required in the process of officiating a football game.

Attention is now directed to FIGURE 5 of the drawing 45 wherein a modification of the signal-indicator device 10 is illustrated. In this modification, the arrangement of the structure 16 takes the configuration of arcuate elements or members 118 and 120 which are attached, secured, joined or formed integral to receive the index 50 and middle fingers, not illustrated, of an individual's hand in a manner similar to the annular ring-like elements 18 and 20 of the modification illustrated in FIGURES 1 and 2. The arcuate elements or members 118 and 120 may be secured, joined or formed integral at a location 144 and may also, in turn, be joined, secured or otherwise integrally formed with the top portion 24 of the housing 22 at a location 146 and with the audible signal 12 at a location 150.

The hand hold structure 16 may be of still another 60 modification, as illustrated in FIGURE 6 of the drawing, wherein the arrangement of the structure 16 includes an elongated bar-like element or member 216 having one end portion joined, secured or formed integral with the bottom portion 26 of the housing 22 at a location 246 with the other end portion thereof being joined, secured or formed integral with the audible signal 12 at a location 210. The bar-like element or member 216 extends between the audible signal 12 and the visual indicator 14 and spaces the audible signal from the visual indicator a distance which corresponds substantially to the thickness of the individual's fingers so that an individual may place the bar-like element or member 216 between the index and middle fingers, not illustrated, of the individual's hand so that the audible signal 12 and

visual indicator 14 will be positioned as described and disclosed above.

While the invention has been described, disclosed and illustrated in terms and forms of the embodiments or modifications which it has assumed in practice, the scope 5 of the invention should not be deemed to be limited by these precise embodiments or modifications herein shown, illustrated, described and disclosed, and it is to be understood that other such embodiments or modifications are intended to be reserved especially as they fall within the 10 scope of the claims herein subjoined.

I claim as my invention:

1. A signal-indicator device comprising, in combination, structure having a plurality of portions secured together to define a chamber, 15 an audible signal comprising a whistle supported by said structure, a visual indicator comprising a disc mounted for rotation within said chamber, said disc having a plurality of indicia thereon for indicating the down of a series of plays and a no down situation in a football game, means for enabling selected ones of the indicia to be positioned as desired so as to be individually viewed by an individual while using the device, said means 25 comprising, a bias for restricting the disc against rotation to maintain a selected one of the indicia in the desired position, said disc further having a part thereof which extends 30 beyond the confines of the structure for engagement by an individual's thumb to enable the disc to be rotated on exertion thereby of a force greater than the force created by the bias to select and position one of the indicia on the disc as desired, and 35 said structure further being provided with an arrangement for enabling the signal-indicator device to be attached to an individual's hand with the audible signal being disposed adjacent the back, the visual indicator being disposed adjacent the palm and the 40 part of the disc being disposed adjacent to the thumb, said arrangement having a portion thereof disposed for positioning between an individual's fingers.
2. A signal-indicator device for officiating football games, said device comprising, in combination, structure 45 defining a chamber, an audible signal secured to said structure, a visual indicator comprising a disc mounted for rotation within said chamber, said disc having a plurality of indicia thereon for indicating the down of a series of plays and a no down situation in a football game, and 50 an arrangement for enabling said device to be carried by an individual's hand with the audible signal being disposed adjacent the back, the visual indicator being 55

disposed adjacent the palm and the disc operably disposed adjacent the thumb thereof, said arrangement having an elongate substantially rigid portion which is adapted to extend between and curve about at least a part of the fingers of such individual's hand.

3. A signal-indicator device comprising, in combination, an audible signal, a visual indicator, and structure connecting the signal and the indicator together, said structure having an elongate substantially rigid portion that is adapted to extend between and about at least a part of the fingers of an individual's hand to enable the device to be carried thereby.
4. A signal-indicator device comprising, in combination, an audible signal, a visual indicator comprising a disc having indicia thereon, structure for connecting the signal and the indicator together, said disc being carried by said structure for movement between a plurality of positions, means for enabling the disc to be retained in a selected one of the positions, and said structure having an elongate substantially rigid portion which is adapted to extend between and curve about at least a part of the fingers of an individual's hand.
5. A signal-indicator device having an audible signal comprising a whistle, a visual indicator comprising a disc having indicia thereon for indicating a down of a series of plays in a football game, and structure for connecting the signal and the indicator together with the disc being rotatably mounted thereon, said structure having an arrangement for enabling the device to be carried by an individual's hand, said arrangement having an elongate substantially rigid portion which is adapted to extend between and about at least a part of an individual's fingers to enable the signal and the indicator to be disposed to opposed sides of an individual's hand with the disc being adjacent the thumb thereof.
